UNITED STATES PATENT OFFICE.

GEORGE J. McGOWAN, OF GRAND RAPIDS, MICHIGAN, ASSIGNOR TO GRAND RAPIDS
REFRIGERATOR CO., OF GRAND RAPIDS, MICHIGAN, A CORPORATION OF MICHIGAN.

DOOR-LATCH.

1,275,954.

Specification of Letters Patent. Patented Aug. 13, 1918.

Application filed November 23, 1915. Serial No. 63,112.

To all whom it may concern:

Be it known that I, GEORGE J. McGOWAN, a citizen of the United States, residing at Grand Rapids, in the county of Kent and State of Michigan, have invented new and useful Improvements in Door-Latches, of which the following is a specification.

This invention relates to door latches and has for its primary object to provide a device of this character having the inherent property of drawing the door into tight engagement with the jamb and at the same time compensating for any shrinkage of the door with the result that a tight fit is had at all times between the door and the jamb which is absolutely necessary in ice boxes or similar receptacles.

An object of the invention is to provide novel means for putting a spring under tension the energy of which when expanding being utilized to draw the door into tight engagement with the jamb, this action being facilitated by a hook that transmits the energy of the spring to a keeper carried by the door.

Another object of the invention is the manner of mounting the trigger or hook so that the same may readily hold the spring under tension but when given a slight movement beyond this position the spring will quickly act for rapidly swinging the hook to a position to rapidly bring the door in close contact with its jamb.

With these and other objects in view the invention consists in the construction, combination and arrangement of parts as will be hereinafter more fully described, illustrated in the accompanying drawing and pointed out in the claim hereunto appended.

In the drawings:

Figure 1 is a fragmentary portion of a door and jamb showing my invention applied thereto,

Fig. 2 is a side elevation of the lock shown applied,

Fig. 3 is a vertical sectional line 3—3 of Fig. 1,

Fig. 4 is a side elevation of the latch with the casing partly in sections. Figs. 5 and 6 are horizontal sectional views through the casing. Fig. 7 is a perspective view of the hook. Fig. 8 is a perspective view of the operating lever.

In the drawings numeral 1 designates a door jamb while the numeral 2 indicates a door of any well known construction such as the type having beveled side edges that incorporates with the beveled surfaces of the jamb, such construction being well known in the manufacture of ice boxes. Arranged in the jamb 1 is a casing 3 that forms one element of my invention. This casing 3 is of a cylindrical shape and has formed integral therewith at an intermediate point a plate 4 provided with openings 5 through which securing elements 6 may be passed so as to secure the casing to the jamb. Arranged in the cylindrical casing is a coil spring 7 that at one end bears upon a disk 8 slidably mounted within the casing and adapted to coöperate with the cam surface 9 of the hook or trigger 10. At this point attention is called to the fact that when the hook is in an inoperative position the cam surface is arranged in alinement with the axis of the spring and the axis of the pivot 11 of the hook with the result that when the hook is in an inoperative position the energy of the spring will be unable to act upon the hook for throwing it about its pivot. The numeral 12 designates the shank of the hook while the numeral 13 indicates the bill. The latter adapted to engage the keeper 14 and an extension formed on a handle 15 that in the initial operation of the latch the keeper or extension 14 engages the shank for giving partial rotation to the hook for allowing the force of the spring to continue such movement for drawing the door into tight engagement with the jamb through the coöperation of the bill with the lug 14.

For returning the hook to a position to contract the spring I provide a lever 16 pivoted upon the plate extension 4 and having its short arm engaging the under surface of the shank of the hook.

From the foregoing description taken in connection with the accompanying drawing the advantages of the construction and of the method of operation will be readily apparent to those skilled in the art to which the invention relates and while I have described the principle of operation of the invention together with the device which I now consider to be the best embodiment thereof I desire to have it understood that the de-

vice shown is merely illustrative and that such changes may be made when desired as are within the scope of the claim.

What I claim is:—

- 5 In combination with a door and door jamb therefor, a casing open at its outer end and inserted partially through the jamb, a spring in the casing, a disk positioned against the spring, a trigger pivotally mounted between the sides of said casing at the outer end thereof, said trigger including an inner shank, and an outer overhanging bill at one side of the pivot therefor and a projecting portion provided with an outer
- 10 cam surface adapted to bear against said disk, a lever pivotally mounted between its
- 15

ends adjacent said trigger, one end of the lever extending under the shank of the trigger, and a striker connected to the door and adapted to pass across the meeting ²⁰ edges of the door and jamb to thereby engage against the shank of the trigger and turn the same as the door is closed to bring the bill over said striker and hold the same against outward movement, substantially as ²⁵ and for the purposes described.

In testimony whereof I affix my signature in presence of two witnesses.

GEORGE J. McGOWAN.
